US0D1097702S

(12) United States Design Patent (10) Patent No.: US D1,097,702 S
(45) Date of Patent: * Oct. 14, 2025

(54) FOOD OR BEVERAGE CONTAINER

(71) Applicant: Crown Packaging Technology, Inc.,
Tinley Park, IL (US)

(72) Inventor: Peter Davies, Wantage (GB)

(73) Assignee: Crown Packaging Technology, Inc.,
Tinley Park, IL (US)

() Term: 15 Years

(21) Appl. No.: 29/891,189

(22) Filed: May 2, 2023

(30) Foreign Application Priority Data

Nov. 2, 2022 (GB) 015002193-0001

(51) LOC (15) Cl. 07-01

(52) U.S. Cl.

USPC D7/509; D7/773; D7/779

(58) Field of Classification Search

USPC D7/507, 509-511, 540, 533-536, 300.1,

D7/300.2, 316, 317, 391, 392.1, 396.1,

D7/396.2, 629, 900, 500; D9/435,

D9/530-531, 773, 779; D3/202

CPC ... A47G 19/2205; A47G 21/18; A47J 41/024;

A47J 41/00; A47J 41/028; B65D 1/00

See application file for complete search history.

(57) CLAIM

The ornamental design for a food or beverage container as shown and described.

DESCRIPTION

FIG. 1 is a top perspective view of a food or beverage container;

FIG. 2 is a bottom perspective view of the food or beverage container of FIG. 1;

FIG. 3 is a top view of the food or beverage container of FIG. 1;

FIG. 4 is a bottom view of the food or beverage container of FIG. 1;

FIG. 5 is first side view of the food or beverage container of FIG. 1; and,

FIG. 6 is a second side view of the food or beverage container of FIG. 1.

1 Claim, 6 Drawing Sheets
